US0D1055076S

(12) **United States Design Patent** (10) Patent No.: **US D1,055,076 S**
(45) Date of Patent: ** Dec. 24, 2024

(54) **MOUNT HEAD AND MONITOR ARM
INCLUDING A MOUNT HEAD**

(71) Applicant: **Humanscale Corporation**, New York, NY (US)

(72) Inventors: **Fabian Monsalve**, New York, NY (US); **Ross Velazquez**, New York, NY (US); **Jacob Glickstein**, Golden Valley, MN (US)

(73) Assignee: **Humanscale Corporation**, New York, NY (US)

(**) Term: **15 Years**

(21) Appl. No.: **29/892,516**

(22) Filed: **May 18, 2023**
